FORMATION TESTER SAMPLE CHAMBER
ASSEMBLYGeorge H. Ramsey, Ardmore, Okla., assignor to
Standard Oil Development Company, a corpora-
tion of Delaware

Application September 25, 1952, Serial No. 311,467

4 Claims. (Cl. 166—1)

1

This invention relates to an improved apparatus for the testing of formations through which a hole is drilled to determine possible oil-bearing strata. The invention is more particularly concerned with a sample chamber designed for employment with suitable formation testers. The apparatus of the present invention comprises a balanced valve sample chamber designed for unsealing over a wide range of hydrostatic pressures. A particular feature of the present invention is a means for counterbalancing the downward force of the drilling mud, which would otherwise tend to prevent a sliding member of the valve from operating satisfactorily.

This application is a continuation-in-part of application Serial No. 123,027, filed October 22, 1949.

In conventional oil well drilling operations, fluids known as drilling muds are employed to aid in carrying away cuttings and also to maintain a hydrostatic head in the well to prevent the uncontrolled escape of gases or liquids from various formations encountered during drilling. One disadvantage of drilling with a drilling mud is that the sampling of natural fluids occurring in various formations is thereby rendered difficult. To overcome this disadvantage, various types of formation testers have been devised which are provided with means for reducing the hydrostatic pressure in the vicinity of the formation to be tested and for establishing communication between the formation and suitable conduits or chambers for collecting the fluid samples with but little or no contamination by drilling mud. Formation testing gives valuable information as to whether or not oil exists in the formation tested. Information can also be obtained relative to the possible productivity of the well, the pressure of the fluids in the rock formation, the ratio of oil to gas, and the occurrence of salt water.

Many of these formation testers are provided with elastic sleeves or packers for sealing off the portion of the well in which it is desired to reduce the hydrostatic pressure. The use of such elastic packers is particularly desirable since such a packer can be expanded to give a thorough seal and yet may be readily removed from the well after being deflated. Furthermore it is possible to position such an elastic packer at any desired point in the well with very little difficulty. With formation testers of this type the use of a retrievable sample chamber is an invaluable aid. Such a sample chamber may be run in and out of the bore hole rapidly and can give positive in-

2

formation as to the production of fluids from a given formation. If a pressure recorder is employed with the sample chamber a pressure record can be obtained, as an indication of conditions existing in the formation. When using a formation tester which may be relocated for any number of tests without withdrawing it from the hole, a retrievable sample chamber may be used to determine the advisability of conducting 10 more extensive tests and many more sections of the well may be evaluated in a relatively short time. However, as the testing depth increases, the difficulty of removing a sample chamber from its seat in the formation testing tool increases. This is due to the hydrostatic head of 15 the drilling mud, which tends to keep the sample chamber in position.

It is an object of the present invention to provide a retrievable sample chamber for use with 20 an oil well formation tester wherein the sample chamber is adapted to seat on a constriction within the formation tester or within the drill pipe associated with the formation tester and wherein the sample chamber may be readily released from its sealed position when it is desired 25 to do so, regardless of the downward force being exerted on the sample chamber by the drilling mud. In accordance with this invention this object is accomplished by providing within the 30 sample chamber a sliding valve which is balanced with regard to opposing hydraulic forces, and by providing means for equalizing pressures above and below the seating area of the chamber when it is desired to free the sample chamber.

35 The nature and objects of this invention may be more readily understood by reference to the accompanying drawings in which:

Figure 1 is a perspective view, in quarter section, of the lower portion of a sample chamber 40 assembly in position within the top portion of a drill stem formation tester using an inflatable packer;

Figure 2 is an elevational view in section showing the sample chamber assembly just above its 45 seating position in the formation tester; and

Figure 3 is an elevational view in section, showing the sample chamber and valve mechanism after the sample chamber has seated and after the valve has moved to its open position.

50 Referring specifically to Figure 1, the upper portion of an inflatable packer 1 is shown attached by fastening means 9 to a mandrel or backing ring 2 which in turn is attached to the lower end of a special section of drill pipe 3. 55 The formation tester illustrated is in general of

the type disclosed in U. S. Patent 2,600,173 of Ben W. Sewell and George H. Ramsey, issued June 10, 1952, and is provided with production tubes 4 containing packing elements 5, an inflation channel 6 and a pressure equalizing channel 7. It is to be understood, of course, that the sample chamber assembly of this invention may also be used with other types of formation testers rather than the one illustrated.

The packer 1 is inflated by pumping drilling mud or other fluid down through the drill pipe into chamber 14 before the retrievable sample chamber has been lowered into place in the drill pipe. The inflation pressure for the inflatable packer may be controlled by any convenient means. For example, a special drill pipe section 3 may be provided with one or more orifices 13 so that fluid may be circulated down through the drill pipe and out through these orifices into the annulus between the drill pipe and the bore hole, thereby setting up a differential pressure between the mud inside the drill pipe and the mud surrounding the drill pipe in the vicinity of the packer. This differential pressure will be independent of the absolute or static pressure in the bore hole and will depend only on the size of the orifices and the mud circulation rate, so that a predetermined pressure is available for inflating the packer. This method of inflating a formation tester packer is described and claimed in co-pending application Ser. No. 202,172 of Ben W. Sewell, filed December 22, 1950.

Deflation of the packer prior to the completion of the test is prevented by a check valve 10 backed by a spring 11 placed in the inflation channel 6. When it is desired to deflate the packer, rod 12 may be depressed by a suitable tool lowered into the drill pipe so as to unseat valve 10. Such means are well known and need not be illustrated here. Escape of fluid from chamber 14 through conduit 8 and production tubes 4 during inflation of the packer is prevented by check valve 15.

After the packer has been inflated a sample chamber is run into the drill pipe on a wire line to collect a sample of the formation fluids through production tubes 4. A lower portion of such a sample chamber assembly is shown in Figure 1, identified by numeral 17. The sample chamber assembly is provided with a sliding valve member having a tapered portion 18 which is adapted to seat on a special shoulder 19 which defines the upper portion of a constricted section of the drill pipe. The sliding valve member is removably retained within the assembly by means of a removable split ring 47. A flexible sealing means comprising a flexible cup 20 is fastened to the bottom of the tapered member 18 by means of a ring 21 and a hex nut 22. This tapered flexible cup is adapted to fit compressibly within the constricted portion of the special drill pipe section to ensure a tight fluid seal which will prevent passage of the drilling mud down into chamber 14 when the hydrostatic pressure is reduced in the latter chamber during the collection of the formation fluids. It is readily apparent that when it is desired to unseat the sample chamber assembly from its position against shoulder 19 and to release the packing cup 20 from the constricted section of the drill pipe the differential pressure between the drilling mud above shoulder 19 and the fluid in chamber 14 will make such unseating difficult. However, the valve arrangement about to be described overcomes this difficulty.

Referring now to Figures 2 and 3 it will be seen

that the body of the sample chamber assembly comprises two sections, an upper section identified by the numeral 16 within which the sample chamber 26 is positioned and a lower section 17 which may be called the valve section. Within the valve section is a valve chamber 27 which slidably receives a valve element 28, which comprises an elongated piston, the lower portion of which extends below the body of the assembly and constitutes the tapered member 18 referred to in Figure 1.

An intermediate portion of valve element 28 is provided with ears 30 that fit slidably in slots 31 in valve section 17. The slidable valve element is held in the position shown in Figure 2 by shear pins 32. The purpose of these shear pins is to prevent the accidental opening of the valve as the sample chamber assembly is lowered through the drill pipe. Valve element 28 is retained within valve chamber 27 by a split ring member 47 that is suitably fastened to the bottom of valve section 17 as, for example, by recessed bolts. It will be seen that when member 47 is in place ears 30 will strike that member and prevent valve element 28 from sliding out of chamber 27. Use of split rings of this nature, which are separable into two or more sections, is common practice when removal of an integral retaining ring from a cylindrical member is not possible because of interfering structure.

Valve element 28 is provided with a central conduit or channel 34 which terminates at its lower end in an exterior port 35 below the packing cup 20 and which terminates at its upper end in a side port 36. Valve chamber 27 is provided at its upper end with a pressure equalizing port 40 which terminates exterior of the valve chamber body. The valve chamber 27 has a central portion 37 of larger bore than the diameter of the valve element 28 and channel 39 is provided to establish fluid communication between the enlarged central portion 37 and the sample chamber 26. Ring seals 42, 43, and 44, mounted in grooves on valve element 28 prevent fluid leakage past this element where it fits slidably within the valve chamber.

It will be noted that with valve element 28 in the position shown in Figure 2, i. e. in the position it assumes as the sample chamber assembly is lowered through the drill pipe, channel 34 provides a path for the flow of drilling mud or other fluid from the region exterior of the assembly below the sealing cup 20 to a region exterior of the assembly above the sealing cup, since port 36 in this position of the valve element registers with one of the slots 31, this slot serving as a side port for the valve chamber. Thus as the tapered member 18 comes to seat on shoulder 19 and flexible cup 20 enters the constricted portion of the drill pipe, fluid thereby displaced from the constricted area is free to flow up through channel 34 and out through the slot 31. This ensures that the assembly will seat properly on the shoulder provided. The sample chamber assembly is lowered with sufficient momentum so that on the impact of seating member 18 on shoulder 19 the pins will be caused to shear. Thus member 17 will continue to travel downward, sliding on element 28 until the bottom end of member 17 comes to rest on shoulder 29 at the top of tapered member 18. The valve will then be in the position shown in Figure 3.

With the sample chamber assembly seated in position and with valve member 28 in the position shown in Figure 3, fluid communication is estab-

lished between chamber 14 and sample chamber 26, the fluid path being provided by channel 34, the enlarged bore 31 and channel 39. As the pressure within chamber 26 is originally at atmospheric pressure or lower whereas the formation pressure is substantially above such pressure, formation fluid will flow into the sample chamber from the production tubes 4 and chamber 14 through the fluid path just described.

After the fluid sample has been secured, the sample chamber is pulled upward by the wire line on which it was lowered into the drill pipe. The arrangement for raising and lowering the sample chamber on the wire line is conventional and hence is not shown in the drawing. As the assembly begins to move upward in the drill pipe, the hydrostatic head of the drilling mud exerted on the sliding valve element 28 above the sealing cup 20 will hold member 18 in position on shoulders 19 until the valve chamber body 17 has slid upwardly with respect to element 28 to the position shown in Figure 2. It will be seen that at this time the enlarged bore 37 will be closed off by element 28 so that fluids within chamber 26 cannot escape and at the same time fluid communication is again established between fluid in the drill pipe above the sealing cup 20 and fluid in chamber 14. Thus fluid pressures above and below the sealing cup 20 and above and below the member 18 become equalized and the seal established by member 18 and cup 20 is readily released.

It will be noted further that any tendency for fluid forces within the drill pipe to move valve element 28 upwardly and thus release fluids from chamber 26 through channel 34 is overcome by the provision of pressure equalizing port 40 positioned above the top of element 28. The top portion of element 28 is of the same diameter as the body of the element so that the top of the element acts as an equalizing piston. Thus any fluid force tending to move element 28 upwardly is overcome by an equal fluid force bearing down on the area 38.

A noteworthy feature of the sample chamber assembly of this invention is that valve element 28 is the only moving part and that all of the pressure seals associated with the valve may be inspected by merely removing this one moving part. For this purpose it is merely necessary to remove the split ring 47 from the lower end of member 17, whereupon valve element 28 will be free to slide out of valve chamber 27.

It is not intended that this invention be limited to the specific embodiments herein described as many modifications thereof are possible without departing from the scope of the invention.

What is claimed is:

1. Improved apparatus for collecting a sample of fluid from the lower end of a drill pipe comprising, in combination, a body adapted to be lowered into said drill pipe, a fluid retaining chamber in said body, a valve chamber in said body, a valve element slidably arranged in said valve chamber, said valve element comprising an elongated piston extending below said body and having a portion adapted for seating on a constriction in said drill pipe, said valve chamber having a first port at its upper end above said

valve element and a second port intermediate its ends, both of said ports terminating exterior of said body, a first conduit in said body connected to said fluid retaining chamber and terminating within said valve chamber, a central conduit within said valve element terminating at one end below said seating portion and at the other end exterior of said valve element at a point intermediate its ends, said valve element assuming within said valve chamber a first position wherein said central conduit is placed in fluid communication with said second port of said valve chamber, and movable to a second position wherein said central conduit is placed in communication with said first conduit, said first port in said valve chamber serving to transmit fluid pressure in said drill pipe to the top of said piston, whereby fluid pressure tending to force said piston upward is counterbalanced.

20 2. Improved apparatus according to claim 1 including packing means supported on said valve element adjacent said seating portion and adapted for fluid sealing engagement with said drill pipe constriction.

25 3. Improved apparatus according to claim 1
including shear pins releasably holding said valve
element in said first position.

4. Improved apparatus for collecting a sample of fluid from the lower end of a drill pipe comprising, in combination, a body adapted to be lowered into said drill pipe, a fluid retaining chamber in said body, a valve chamber in said body, a valve element slidably arranged in said valve chamber, said valve element comprising an elongated piston extending below said body and having a portion adapted for seating on a constriction in said drill pipe, said valve chamber having a central portion of larger bore than said valve element and having a first port at its upper end

30 35 40 above said valve element and a second port intermediate its ends, both of said ports terminating exterior of said body, a conduit in said body connecting said enlarged bore of said valve chamber with said fluid retaining chamber and a central

45 with said fluid retaining chamber and a central conduit within said valve element terminating at one end in a side port exterior of said valve element at a point intermediate the ends of said valve element, and terminating at the other end in a bottom port exterior of said valve element below said seating portion, said valve element 50 assuming within said valve chamber a first position wherein said side port communicates with said second port of said valve chamber and movable to a second position wherein said side port 55 communicates with said enlarged bore of said valve chamber, said first port in said valve chamber serving to transmit fluid pressure in said drill pipe to the top of said piston, whereby fluid pressure tending to force said piston upward is counterbalanced.

GEORGE H. RAMSEY.
